UNITED STATES PATENT OFFICE

LEON B. LENT, OF LAKewood, OHIO

DESIGN FOR AN AUTOMOTIVE VEHICLE

Application filed November 21, 1931. Serial No. 41,795. Term of patent 14 years.

To all whom it may concern:

Be it known that I, LEON B. LENT, a citizen of the United States, residing at Lakewood, in the county of Cuyahoga and State of Ohio, have invented a new, original, and ornamental Design for an Automotive Vehicle, of which the following is a specification, reference being had to the accompanying drawings, forming part thereof, wherein Figs. 1, 2 and 3 are top plan, side elevational and front elevational views, respectively.

I claim:—

The ornamental design for an automotive vehicle, substantially as shown.

LEON B. LENT.
